UNITED STATES PATENT OFFICE.

WILLIAM R. FARNSWORTH, OF TURNER'S FALLS, MASSACHUSETTS.

EXPANDING PLUG FOR ARBORS OF PAPER-ROLLS.

SPECIFICATION forming part of Letters Patent No. 533,451, dated February 5, 1895.

Application filed June 5, 1894. Serial No. 513,534. (No model.)

To all whom it may concern:

Be it known that I, WILLIAM R. FARNSWORTH, a citizen of the United States, residing at Turner's Falls, in the county of Franklin and State of Massachusetts, have invented 5 new and useful Improvements in Expansible Plugs for the Arbors of Paper-Rolls, of which the following is a specification.

This invention relates to improvements in 10 shafts having expanding devices whereby the shaft may be readily set within the tubular core of a roll of paper so that the shaft temporarily becomes the journal or arbor for the roll as desired while the roll is being made up 15 at the mill, or while the paper is being used on a printing press.

The purpose of the present improved device is to accomplish more effectually, and by simpler and less expensive means, the results 20 in a manner attained by the employment of the expansible shaft set forth in Letters Patent of the United States granted to me September 8, 1891, No. 459,200, for improvements in expansible shafts, and the invention consists 25 in constructions and combinations of parts all substantially as will be hereinafter fully set forth and pointed out in the claims.

Reference is to be had to the accompanying drawings which form part of this specification, 30 and in which—

Figure 1 is a longitudinal sectional view through a tubular cored paper roll and in part through the arbor and one of the expansible "plugs" or devices which surround the arbor, 35 said view being also in part a side view of the shaft and the other plug of the pair of plugs used in conjunction therewith. Figs. 2 and 3 are cross sectional views on lines 2—2 and 3—3, Fig. 1. Fig. 4 is a perspective view of 40 one of the segments, and Fig. 5 is a perspective view of one of the sliding tapered bars.

Similar characters of reference indicate corresponding parts in all of the views.

In the drawings x represents the roll of paper having the tubular core x^2 .

A represents the tubular body of the plug which is adapted to be removably fixed to the shaft C . The said cylindrical tubular body A has at its inner end the external flange c , 50 and the several longitudinal grooves or ways, b , b .

B , B represent the side bars, which are mov-

able in said ways b . Each bar comprises at one-half, or other suitable portion, of its length the transversely dovetailed and longitudinally tapered outstanding member d , while its shank or other half has at its outer side the series of screw-thread-sections f , f . 55

D , D represent the segments which along their inner sides have dovetail ways g therein, 60 within which the outstanding dovetailed portions of the bars B engage. The segments have their opposite sides curved approximately corresponding to the inner peripheral contour of the opening through the roll, or the 65 core thereof.

The aforesaid tubular body, A , of the plug has intermediate between its ends the outstanding separated wings or flanges a , which are arranged between the aforesaid longitudinal ways b . These prevent the segments from having any outward endwise motion while they may have no inward endwise motion by reason of the abutment of their flanges, j , 70 against the end of the roll or by the contact 75 of their inner ends against the annular flange, c , of the tube A . Next outside of the said wings, a , a of the tubular body, A , and concentrically surrounding the latter is the circular nut G , the teeth of which screw engage 80 the sections of threads f of the slide bars, B , B , and this nut is provided with spanner holes or is otherwise adapted to be conveniently turned by any suitable implement. Next outside of the nut G is a collar, m , which fits 85 about the tubular body, A , being secured thereto, preferably removably as by the set screw n . This set screw also projects radially inwardly through the tubular body, A , to temporarily hold the plug as a whole in its 90 place upon the shaft.

The nut lying between the wings, a , of the tubular body, A , and the collar, m , thereof, of course can have no endwise movement, while its rotational movement will effect the endwise movement of the tapered slide-bars, B . The nut holds the slide bars to the body and the slide bars, by reason of the dovetail engagements which they have with the segments, keep the latter from radial displacement. 95 The said collar has longitudinal apertures internally, one of which is seen at m^2 to accommodate and permit the outward movement of the slide bars. 100

A shaft equipped with the plugs substantially as described, may be readily utilized as the journal for a roll of paper, for instance in the following manner, it being understood that one of the plugs may be moved endwise along and off from the shaft:—The plugs are contracted and the right hand one slid outwardly along and off the shaft so that the shaft may be brought endwise into and through the roll to place its plug which is at its other end portion and which has not necessarily been loosened within the mouth of the roll opening. The second plug is now brought to place on the shaft and within the mouth of the opening at the other end of the roll and there secured by its set screw. The two plugs are now expanded by forcing the segments radially outward through the manipulation of their nuts sufficiently far and hard to render the roll and its shaft or arbor temporarily as a unit.

I claim—

1. The combination with the tubular body having externally the longitudinal ways, of slide bars guided in said ways which have threaded portions, and tapered portions, tapered segments having dovetail ways in which the tapered portions of the said bars have sliding engagements, the nut surrounding and screw engaging the threaded parts of the slide bars and means for preventing endwise movement of the nut, substantially as described.
2. The combination with the tubular body having externally the longitudinal ways, of the slide bars guided in said ways having the beveled portions, and the threaded portions, the segments having the dovetail slide engagement with the beveled portions of said bars and the nut surrounding the threaded portions of the bars and holding the bars against radial displacement, while said bars by their dovetail engagement with the segments, prevent the latter from radial displacement, substantially as described.
3. The combination with the tubular body having externally therein the longitudinal ways and the bars B sliding longitudinally in said ways which have the outstanding tapered and dovetail portions, *d*, and the threaded portions, *f*, of the wedge-formed segments having the dovetail grooves in which the portions, *d*, of the said bars fit, and with which segmental

projections which are provided on the tube engaged for preventing their outward endwise movement the nut surrounding the threaded extremities of the bars and means for preventing its axial movement while it is left free to turn, substantially as described.

4. The combination with the tube A having intermediate between its ends the separated wings or flanges, *a*, and the external longitudinal ways, *b*, ranging between said wings of the bars B set to slide in said ways and having the outstanding longitudinally wedge-formed and transversely dovetailed portions, *d*, and the shank, *f*, having the sections of screw threads, the segments D having the dovetail engagements with the said bars, B, the nut surrounding and in engagement with the threaded - shank - bars and at one edge bearing against said wings, and the collar secured upon the outer end of the tube and constituting the other side bearing for said nut, substantially as described.

5. The combination with the tubular core 75 for the paper roll and the shaft having thereon within each end of the core the tube B which has externally the longitudinal ways, of the bars movably fitted in said ways each having the threaded portions and the tapered 80 portion, the segments having the dovetailed ways, the nut surrounding and screw engaging the threaded portions of the bars, and means for preventing the endwise movements of the nut, substantially as described. 85

6. The combination with the tubular body having the longitudinal ways, *b*, of the slide bars movable along said ways and having the tapered and dovetail portions, *d*, and the portions *f* with the sections of screw threads, the 90 tapered segments with the dovetail ways in which the portions *d* of said slide bars engage, the nut, G, surrounding and in screw-engagement with the threaded portions of the slide bars and the collar removably secured 95 upon the tubular body and having, internally, longitudinal apertures within which play the extremities of the slide bars, substantially as described.

WILLIAM R. FARNSWORTH.
